CLAIM

The ornamental design for an insulating device, as shown and described.

DESCRIPTION

FIG. 1 is a top, front, right perspective view of an insulating device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The even-length broken lines immediately adjacent to the shaded areas represent unclaimed boundaries of the design. The even-length and uneven-length broken lines showing the remainder of the insulating device form no part of the claimed design. The unshaded regions within or adjacent to the shaded area form no part of the claimed design.
